(57) **CLAIM**

We claim the ornamental design for a wristband case, as shown and described.

DESCRIPTION

FIG. 1 is a top rear perspective view of a first embodiment of a wristband case showing our new design.

FIG. 2 is a bottom rear perspective view of the wristband case of FIG. 1.

FIG. 3 is a bottom front perspective view of the wristband case of FIG. 1.

FIG. 4 is a side view of the wristband case of FIG. 1.

FIG. 5 is an opposing side view of the wristband case of FIG. 1.

FIG. 6 is a top view of the wristband case of FIG. 1.

FIG. 7 is a bottom view of the wristband case of FIG. 1.

FIG. 8 is a front view of the wristband case of FIG. 1.

FIG. 9 is a rear view of the wristband case of FIG. 1.

FIG. 10 is a top rear perspective view of a second embodiment of a wristband case showing our new design.

FIG. 11 is a bottom rear perspective view of the wristband case of FIG. 10.

FIG. 12 is a bottom front perspective view of the wristband case of FIG. 10.

FIG. 13 is a side view of the wristband case with peg component of FIG. 10.

FIG. 14 is an opposing side view of the wristband case with peg component of FIG. 10.

FIG. 15 is a top view of the wristband case with peg component of FIG. 10.

FIG. 16 is a bottom view of the wristband case with peg component of FIG. 10.

FIG. 17 is a front view of the wristband case with peg component of FIG. 10; and,

FIG. 18 is a rear view of the wristband case of the wristband case of FIG. 10.

The second embodiment of the design includes a peg component inserted in the end of the back wrist strap but is otherwise identical to the first embodiment.

In the drawings, the portions indicated with dashed lines, dotted lines, or otherwise broken lines, including all text, show portions of the wristband case which form no part of the claimed design.

The wristband portions of the design are shown with a break in their length represented by broken lines. The appearance of any portion of the article between those breaks forms no part of the claimed design.
